INKING MECHANISM FOR PRINTING MACHINES

William F. Huck, Richmond Hill, N. Y., assignor to
R. Hoe & Co., Inc., New York, N. Y., a corpora-
tion of New York

Application June 28, 1941, Serial No. 400,308

17 Claims. (Cl. 101—348)

This invention relates to inking mechanism, and more particularly to inking mechanism to be employed in modern rotary printing machines.

It has been found from experimentation and also from practice in the commercial field that the most satisfactory inking mechanism for modern rotary printing machines incorporates rotary and reciprocatory components. Such inking mechanism usually includes one or more rotary ink distributing cylinders which cooperate with suitable ink rollers to work the ink into a uniform film of required thickness before it is deposited onto the plate or form cylinder by the conventional form roller or rollers. In order to produce the best result, the ink cylinder should be suitably reciprocated as well as rotated.

Rotary motion is usually imparted to the ink cylinders through the instrumentality of gears and the like, but various means have been employed to reciprocate these cylinders. Heretofore, cams, links, rocker arms, bell cranks and other devices have been employed to reciprocate the ink cylinders in some designs, and in others, eccentrics and connecting rods have been utilized.

In existing inking mechanisms, separate rotatable members are employed to initiate the motion which finally results in imparting reciprocatory movement to the ink cylinders. It is, therefore, an object of this invention to provide novel instrumentalities for reciprocating the ink cylinders or other components of the inking mechanism by the rotary motion of the ink cylinders.

Another object of the invention is to provide an inking mechanism for rotary printing machines in which the rotary motion of the inking component which is to be reciprocated imparts rotary movement to an actuator which, in turn, imparts reciprocatory motion to the said inking component.

A specific object of this invention is to provide an inking mechanism for rotary printing machines in which a rotary member or actuator is provided with helical ribs or grooves to cooperably engage rollers carried by rotary inking components and provided with annular ribs or grooves whereby reciprocatory motion is imparted to the inking components.

A more specific object of this invention is to provide an inking mechanism for rotary printing machines in which a rotary member or actuator is provided with helical ribs or grooves to cooperably engage rollers carried by rotary inking components and provided with annular ribs or grooves whereby reciprocatory motion is im-

parted to the inking components, and these rotary inking components being operably connected to ink rollers to reciprocate them relative to other rotary components of the inking mechanism.

It is also an object of this invention to provide an inking mechanism for printing machines of generally improved construction, whereby the device will be simple, durable, and inexpensive in construction, as well as convenient, practical, serviceable and efficient in its use.

With the foregoing and other objects in view, which will appear as the description proceeds, the invention resides in the combination and arrangement of parts and in the details of construction hereinafter described and claimed, it being understood that various changes in form, proportion, and minor details of construction may be made within the scope of the claims without departing from the spirit or sacrificing any advantages of the invention.

For a complete disclosure of the invention, a detailed description thereof will now be given in connection with accompanying drawings forming a part of the specification, wherein:

25 Figure 1 is a vertical fragmental sectional view taken through a printing machine and showing the invention applied thereto;

Figure 2 is a vertical sectional view taken on the line 2—2 of Figure 1 and looking in the direction of the arrows;

Figure 3 is a detailed fragmental vertical section depicting the mechanism for reciprocating the ink cylinders;

Figure 4 is a fragmental horizontal sectional view taken on line 4—4 of Figure 2;

Figure 5 is a fragmental vertical sectional view similar to Figure 3, but depicting a modified form of the invention;

Figure 6 is a vertical sectional view similar to Figure 2, but depicting a modified form of the invention, and

Figure 7 is a fragmental sectional view depicting the speed change mechanism.

Referring to the drawings in which similar reference characters designate corresponding parts, there is depicted a rotary printing machine which includes frame components 10 having bearings 11 to slidably and rotatably support the shafts 12 and 13 of first and second ink cylinders 14 and 16 of an inking mechanism. The inking mechanism includes transfer rollers 17 (Figure 2) which are rotatably supported in bearings provided in the machine frame components 10, and these rollers operably engage the first or lower ink cylinder 14. Similar transfer

rollers 18 operably engage the first or lower ink cylinder 14 and the second or upper ink cylinder 16, and these rollers are rotatably supported in bearings provided in the machine frame components 10. Conventional form rollers 20 are rotatably supported in position to operably engage the upper ink cylinder 16 and plates 21a on a conventional plate cylinder 21.

In this arrangement, ink may be supplied to the components of the inking mechanism by an ink rail or fountain, in conformity with the usual practice, and inasmuch as the initial ink supply does not form a part of this invention, such ink supply mechanism has not been illustrated. The ink is worked into a uniform film by the cooperative engagement of the ink cylinders 14 and 16 and the transfer rollers 17 and 18 and other components of the inking mechanism. The ink film is conveyed from the upper or second ink cylinder 16 through the instrumentality of the form rollers 20, and this ink is then deposited in the usual manner on the forms carried by the plates 21a on form cylinder 21.

The rotary movement of the ink cylinders 14 and 16, transfer rollers 17 and 18, and the other ink rollers of the inking mechanism tends to work the supplied ink into a uniform film before it is deposited onto the plates on the plate cylinder 21, but it has been found from practice that a better distribution of the supplied ink may be effected and a more uniform film supplied if components of the inking mechanism are reciprocated as well as rotated. Therefore, this invention is directed to novel means for reciprocating the ink cylinders and other selected components of the inking mechanism.

In the form of the invention depicted in Figures 1 to 4, the outer terminals of the ink cylinder shafts 12 and 13 are provided at one side of the machine with composite grooved or ribbed rollers, indicated generally at 22 and 23 (Figure 3). These terminals of the ink cylinder shafts 12 and 13 are provided with reduced portions 24 and 26 for the reception of annular members or rings 27, which form the rollers 22 and 23, and these rings are provided with axial bores 28 which snugly engage the peripheral surfaces of reduced portions 24 and 26 of the ink cylinder shafts 12 and 13. Each ring 27 is provided at its outer portion with a tapered or frusto-conical surface 29, and one face of the ring is provided with a relatively narrow radially disposed annular surface 31, and its opposed face is provided with a relatively broad radially disposed annular surface 32. A cylindrical peripheral surface 33 is interposed between the outer terminals of the frusto-conical surface 29 and the radial surface 32 of each ring 27. The rings 27 are positioned on the reduced portions of the ink cylinder shafts 12 and 13 in back-to-back relation with their surfaces 32 in abutting engagement. By this arrangement, the opposed frusto-conical surfaces 29 and the cylindrical surfaces 33 of the rings 27 define composite tapered annular ribs 30 which operably engage similar tapered annular ribs 35 which extend inwardly from the inner peripheral surface 36 of a cylindrical drive member or actuator 37. The drive member or ring 37 is preferably provided, in the form of the invention depicted, with three tapered ribs 35, although it is to be understood that any preferred number of ribs may be utilized to meet required conditions. In the depicted arrangement, six rings or annular roller components 27 are utilized to pro-

vide each composite roller, and the surfaces 29 of the roller sections 27 form tapered recesses for the reception of the tapered ribs 35 of the actuator ring 37, so that, in effect, the ribs 30 of the rollers 22 and 23 engage recesses of similar configuration formed in the drive ring 37, and, conversely, the ribs 35 of the drive ring 37 are received in recesses of similar configuration formed in the rollers 22 and 23. In order to insure that the ribs 30 of the rollers 22 and 23 accurately engage the ribs 35 of the drive ring 37, annular washers or spacers 38 are positioned between each pair of rings 27, and these spacers are located to engage the narrow radially disposed annular surfaces 31 of the roller components 27. The thickness of the spacers 38 is accurately determined to insure that the ribs 30 formed by each pair of rings 27 accurately engage the ribs 35 formed on the actuator ring 37. The rings 27 are clamped against rotation on the reduced portions 24 and 26 of the ink cylinder shafts 12 and 13 by shoulder screws 39, and each screw is held against rotation by a suitable lock screw 40.

The drive ring or actuator 37 is rotatably supported by a cylindrical hub 41 having a radially extending flange or spoked portion 42, and the outer or peripheral portion 43 of the flange 42 is suitably secured to the actuator ring 37 by bolts 45, or other suitable securing devices. The cylindrical hub 41 is rotatably supported by spaced anti-friction bearings 46, which, in turn, are supported by a stud 47. A flange or collar 48 is formed at the inner terminal of the stud 47, and this collar is secured to a frame component 10 by means of a threaded projection or screw 50 which is threaded into a threaded aperture 51 formed in the frame component 10. The collar 48 is preferably held against rotation by means of a lock screw 52 which extends through an aperture 53 formed in the collar or flange 48 and is threaded into the frame component 10. The hub 41 is held against longitudinal or axial movement on the stud 47 by means of a thrust or securing screw 55 which is provided with a threaded stem 56 that threaded into a threaded aperture 57 formed in the stud 47. The securing screw 55 is preferably held against rotation by a lock screw 58 which extends through the head of the screw 55 and is threaded into the stud 47, as indicated at 59.

The head of the screw 55 engages the inner race ring of the outer anti-friction bearing unit 46, and this ring in turn engages a spacing or retaining sleeve 60 which is axially interposed between the inner and outer anti-friction bearing units 46.

By this arrangement, the actuator ring 37 is mounted for free rotary movement about the stud 47, and in order to impart reciprocatory movement to the spaced ink cylinders 14 and 16, the ribs 35 formed at the inner face 36 of the actuator ring 37 are arranged in parallelism, and each rib forms a helix which varies in pitch and reverses itself at diametrically opposed points on the ring 37, so that at the reversal points the rib forms a segment of a true ring. The ribs 35 are preferably disposed to impart reciprocatory movement to the ink cylinders 14 and 16 similar to the reciprocatory movement which would be imparted by a crank and pitman mechanism. The frictional engagement of the ribs 30 of the rotating rollers 22 and 23 causes the actuator 37 to rotate, and the helical disposition of the ribs 35 of the actuator ring 37

causes the rollers 22 and 23 and cylinders 14 and 16 to reciprocate, as will be more fully explained hereinafter.

In the form of the invention disclosed in Figures 1 to 4, a composite yoke 61 (Figures 2 and 4) is pivotally secured to the shaft 12 at each end of the lower ink cylinder 14. Each composite yoke includes a yoke arm or beam 62 having an arcuate or semi-circular intermediate portion 63, and a complementary semi-circular bearing cap 65 which is secured to the yoke arm 62 by machine screws 66, or other suitable securing devices. An anti-friction bearing unit 67, is operably interposed between the shaft 12 of the lower ink cylinder 14 and the arcuate or semi-cylindrical portion 63 of the yoke arm 62 and the bearing cap 65. The bearing receiving semi-cylindrical portion 63 of the yoke arm 62 and the complementary bearing receiving portion of the bearing cap 65 are slightly larger in diameter than the outer race ring of the anti-friction bearing unit 67 so that a slight floating action is permitted between the composite yoke 61 and its supporting shaft 12. By this arrangement, the yoke 61 is mounted for free rotary action in floating relation about the shaft 12 of the lower ink cylinder 14. Each composite yoke 61 is held against axial movement on the shaft 12 of the lower ink cylinder 14 by means of a shoulder 68 formed on the shaft 12, and a collar 70 which is secured to the shaft, the shoulders 68 and collar 70 engaging components of the anti-friction bearing units 67 to thus hold the bearing yokes against axial movement on the shaft 13. Each yoke arm 62 extends laterally to each side of the ink cylinder shaft 12 and terminates in cap bearings 71, that house anti-friction bearings 72, which, in turn, rotatably support shafts 73 formed at the opposite terminals of rider ink rollers 75. Inasmuch as the composite yokes 61 are held against axial movement relative to the lower ink cylinder, it is manifest that any reciprocatory motion that is imparted to the ink cylinder 14 will also be imparted, through the instrumentality of the yokes, to the rider rollers 75, as will be more fully explained hereinafter.

The ink cylinders 14 and 16 may be rotatably driven by any suitable driving mechanism, and a preferred arrangement includes a gear 76 carried by and rotatable with the shaft of plate cylinder 21, and this gear meshes with an idler gear 77 rotatably mounted on a stud 78 which is secured to a machine frame component 10. The idler gear 77, in turn, meshes with a gear 80 carried by and rotatable with the shaft 13 of the second ink cylinder 16. An idler gear 81 is rotatably supported on a stud 82 which is secured to a machine frame component 10, and this gear meshes with the gear 80 of the second ink cylinder and a similar gear 83 which is carried by and rotatable with the shaft 12 of the first ink cylinder 14. By this arrangement, the ink cylinders 14 and 16 are rotatably driven in the same direction, and inasmuch as the ink cylinders engage the transfer rollers 17 and 18, these transfer rollers are rotatably driven, and the rollers 17, in turn, impart rotary movement to the rider rollers 75.

An oil-tight housing 85 (Figure 3) is suitably secured to a machine frame component by screws or other securing devices 86, and this housing completely encloses the actuator ring 37 and cooperating rollers 22 and 23. Suitable oil or grease is carried in the housing 85 to thus lubricate the housed components, and the housing also

protects these components against dust and other extraneous matter.

In operation, the ink cylinders 14 and 16 are rotatably driven in the manner disclosed, and these cylinders, in turn, rotate the composite rollers 22 and 23, and inasmuch as the annular ribs 30 of the rollers 22 and 23 frictionally engage the helically disposed ribs 35 of the drive ring or actuator 37, the actuator 37, in turn, is rotatably driven by the rotation of the rollers 22 and 23. The helical disposition of the ribs 35 of the ring 37 causes these ribs to move the ink cylinders 14 and 16 axially in opposed directions during each revolution of the ring 37. Thus it is seen that the rotary motion of the ink cylinders 14 and 16 imparts rotary movement to the drive ring or actuator 37, and this ring, in turn, imparts reciprocatory movement to the ink cylinders. The amplitude of reciprocatory movement of the ink cylinders 14 and 16 may be determined by the helical disposition of the ribs 35 of the drive ring or actuator 37. In the arrangement depicted, the drive ring 37 moves each ink cylinder through a complete to and fro cycle of movement during each revolution of the ring 37, but it is to be understood, of course, that the helical ribs 35 may be so disposed relative to the ring 37 as to impart any preferred number of reciprocations to the ink cylinders 14 and 16 during each revolution of the drive or actuator ring 37.

In conformity with the usual practice, the requisite quantity of ink is initially supplied to the first ink cylinder 14 by an ink rail or other suitable ink supply instrumentality, not shown, and inasmuch as this ink cylinder rotates, and also reciprocates relative to the transfer rollers 17 and 18, the ink is worked into a film on this cylinder. As the cylinder 14 reciprocates, it also, through the instrumentality of the yokes 62, reciprocates the rider rollers 75 relative to the axially stationary transfer rollers 17, thereby again working the ink to produce a uniform film. Since a slight floating motion is provided between the ink cylinder shaft 12 and the yoke 61, the rider rollers 75 rest on the transfer rollers 17, but they are maintained in operable relation to the transfer rollers 17 by these yokes. From the first ink cylinder 14, the ink is transferred to the axially stationary transfer rollers 18 and then to the rotary and reciprocatory second ink cylinder 16. From the second ink cylinder 16, the ink is deposited onto the form roller or rollers 20 and then conveyed as a uniform film to the plate or form on the conventional plate or form cylinder 21.

In the form of the invention hereinbefore disclosed, rider rollers 75 operably engage the lower transfer rollers 17, but, if preferred, similar rider rollers may be provided for operable cooperation with the upper transfer rollers 18 by merely duplicating the rider roller reciprocating mechanism as depicted in Figure 6. In this arrangement, a yoke 61a is operably secured to the shaft 13 of the upper ink cylinder 16 in the same manner that the yoke 61 is secured to the shaft 12 of the lower or first ink cylinder 14. Rider rollers 75a, similar to the rider rollers 75, are rotatably secured to the opposed terminals of the yoke 61a, so that the rider rollers 75a reciprocate relative to the axially stationary transfer rollers 18 in synchronism with the reciprocatory movement of the upper or second ink cylinder 16. By this arrangement, both ink cylinders 14 and 16 reciprocate rider rollers relative to the engaged transfer

rollers. Alternatively, these rider rollers 75a may be arranged to engage the lower side of the form rollers 20 if desired. Since in such an arrangement, floating motion is opposed by gravity, springs or any other convenient means may be employed to maintain the required upward pressure on the yoke 61a.

In the mechanism hereinbefore disclosed, the drive or actuator ring 37 is rotatably driven through frictional engagement with the rotatably driven rollers 22 and 23, but if preferred, the drive or actuator ring 37 may be positively driven as depicted in Figure 5 of the drawings.

In the arrangement depicted in Figure 5, a countershaft 86 is rotatably mounted in a bearing 87 supported by a machine frame component 10. A relatively long spur gear 88 is secured to one terminal of the shaft 86, and this gear meshes with a relatively narrow gear 90, which is secured to the shaft 13 of the upper or second ink cylinder 16. The terminal of the shaft 86 which is remote from the gear 88 has a spur gear 91 secured thereto, and this gear meshes with a relatively large gear 92 formed on or secured to the exterior of the drive or actuator ring 37a. Thus, it is seen that as the ink cylinder 16 rotates, the gear train 90, 88, 91 and 92 rotatably drive the actuator ring 37a. This ring is provided with the helically disposed ribs 35, hereinbefore disclosed, which cooperate with the ribs 30 of the rollers 22 and 23, to thereby impart reciprocatory movement to the ink cylinders 14 and 16 in the manner hereinbefore disclosed.

When the ratio of the gearing between the shaft 13 and the actuator ring 37a is such that the pitch line of the engaging surface of the roller 23 and the pitch line of the tapered ribs 35 on the actuator ring 37a move at the same speed, the rollers 22, 23 are preferably secured to the shafts 12, 13 as shown in Figure 3, but it will be understood that by the use of gearing which rotates the actuator ring 37a at such speed that the pitch line of the tapered ribs 35 moves at a different speed from that of the pitch line of the rollers 22, 23, the rate of reciprocation of the cylinders 14, 16 will be different, but in such case, it is preferable to permit the rollers 22, 23 to rotate on the shafts 12, 13 and thereby avoid slippage between them and the tapered ribs 35. This is accomplished by removing the locking screws 40 and backing off the shoulder screws 39 sufficiently to permit the free rotation of the composite rollers 22 and 23 on the reduced portions 24 and 26 of the ink cylinder shafts 12 and 13. The locking screws 40 may then be reinserted in the shafts to secure the shoulder screws 39 in their newly adjusted position.

If a gear 88 having a lesser number of teeth, and a mating gear 90 having a greater number of teeth than those shown in Figure 5 are used, the actuator ring 37a will be driven at a higher speed, and the ink cylinders 14, 16 will make fewer rotations during each reciprocating cycle, and conversely, if a gear 88 having a greater number of teeth, and a mating gear 90 having a lesser number of teeth than those shown are used, the actuator ring 37a will be driven at a slower speed, and the ink cylinders 14, 16 will make a greater number of rotations during each reciprocating cycle. The gears 88 and 90 may be arranged as change gears and by using a suitable pair, the rate of reciprocation of the ink cylinders may be changed if desired. Such an arrangement is disclosed in Figure 7, in which gears 88a and 88b are keyed to and slidably mounted

on a shaft 86a, and the gear 88a is shown in mesh with the gear 90. The shaft 86a drives the actuator ring 37a through the interposed gear 91, in a manner hereinbefore disclosed.

5 When it is desired to change the rotational speed of the ring 37a, the gear 88a is slid along the shaft 86a from engagement with the gear 90, and the gear 88b is moved into meshing engagement with the gear 90a. The gear 88b has a smaller number of teeth than the gear 88a, and the gear 90a has a greater number of teeth than the gear 90, to thereby increase the speed of rotation of the actuator ring 37a. The gears 88a and 88b may be slid along the shaft 86a by a conventional manipulating lever 95. This speed change arrangement is of conventional structure which is well understood by those skilled in the art.

Obviously, the actuator ring 37a may be rotated by other means than from the shaft 13, 20 such as by gearing or other suitable connection to any convenient rotating member of the machine, and if frequent adjustment of the rate of reciprocation of the cylinders 14, 16 with respect to their rotation is desired, this may easily be arranged by interposing a suitable form of variable speed device in the gear train between the driving member and the actuator ring 37a.

It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the mechanism herein disclosed forms a part of the invention included in this application.

What I claim is:

1. In an inking mechanism for a printing machine, a rotatable ink cylinder, an annularly ribbed roller connected to the cylinder to rotate therewith, and a rotatable ring having reversing helically disposed internal ribs arranged to engage the ribbed roller and be rotated thereby to reciprocate the ink cylinder.

2. In an inking mechanism for a printing machine, a freely rotatable ring held against axial movement and having reversing helical internal ribs, a rotatable ink cylinder, an annularly ribbed roller connected to the cylinder to rotate therewith, and means to support the ribbed roller in engagement with the ribs of the rotatable ring, whereby rotation of the ink cylinder will rotate the ring and the cylinder will be reciprocated.

3. In an inking mechanism for a printing machine, a rotatable ink cylinder, an annularly ribbed roller connected to the cylinder to rotate therewith, a rotatable ring having reversing helically disposed internal ribs arranged to engage the ribbed roller, and gearing to rotate the ring and thereby reciprocate the ink cylinder.

4. In an inking mechanism for a printing machine, a rotatable ring having reversing helical internal ribs, means to rotate the ring, and a pair of rotatable ink cylinders each having an annularly ribbed roller rotating therewith and engaging the ribs of the rotatable ring, the said ink cylinders being oppositely disposed with respect to the axis of the ring, whereby the cylinders will be reciprocated in opposite directions when the ring is rotated.

5. In an inking mechanism for a printing machine having rotary ink cylinders, means for rotatably driving the rotary ink cylinders, a rotary member rotatably driven by the rotary ink

cylinders, a roller secured to and rotatable with each ink cylinder, annular ribs carried by each roller, and reversing helically disposed ribs carried by the rotary member and operably engaging the ribs of the rollers to impart reciprocatory movement to the ink cylinders.

6. In an inking mechanism for a printing machine having a rotary ink cylinder, means for rotatably driving the rotary ink cylinder, a rotary member rotatably driven by the rotary ink cylinder, and means carried by the rotary member for operably engaging the rotary ink cylinder to impart reciprocatory movement thereto, inking rollers operably engaging the ink cylinder, rider rollers operably engaging the inking rollers, and means for operably connecting the rider rollers with the ink cylinder whereby reciprocatory motion is imparted to the rider rollers by the reciprocatory movement of the ink cylinder.

7. In an inking mechanism for a printing machine having first and second rotary ink cylinders, means for rotatably driving the rotary ink cylinders, a rotary member rotatably driven by the ink cylinders, means carried by the rotary member for operably engaging the rotary ink cylinders to impart reciprocatory movement thereto, first ink rollers operably engaging the first ink cylinder, second ink rollers operably engaging the first and second ink cylinders, first rider rollers operably engaging the first ink rollers, second rider rollers operably engaging the second ink rollers, means for operably connecting the first rider rollers with the first ink cylinder, and means for operably connecting the second rider rollers with the second ink cylinder whereby reciprocatory movement is imparted to the rider rollers by the reciprocatory movement of the ink cylinders.

8. In an inking mechanism for a printing machine having first and second rotary ink cylinders disposed in substantially vertical alignment, means for rotatably driving the rotary ink cylinders, a rotary member rotatably driven by the ink cylinders, means carried by the rotary member for operably engaging the rotary ink cylinders to impart reciprocatory movement thereto, first ink rollers operably engaging the first ink cylinder and disposed in substantially horizontal alignment, second ink rollers operably engaging the first and second ink cylinders and disposed in substantially horizontal alignment, first rider rollers operably engaging the first ink rollers and disposed in substantially horizontal alignment, second rider rollers operably engaging the second ink rollers and disposed in substantially horizontal alignment, means for operably connecting the first rider rollers with the first ink cylinder, and means for operably connecting the second rider rollers with the second ink cylinder whereby reciprocatory movement is imparted to the rider rollers by the reciprocatory movement of the ink cylinders.

9. In an inking mechanism for a printing machine having a rotary ink cylinder, means for rotatably driving the rotary ink cylinder, a rotary member rotatably driven by the rotary ink cylinder, means carried by the rotary member for operably engaging the rotary ink cylinder to impart reciprocatory movement thereto, axially stationary rotatable ink rollers operably engaging the ink cylinder and rotatable thereby, rider rollers operably engaging the axially stationary ink rollers, a yoke rotatably supported by the ink cylinder but secured against axial movement relative thereto, and means for rotatably secur-

ing the rider rollers to the yoke, the rider rollers being secured against axial movement relative to the yoke whereby reciprocatory movement of the cylinder is imparted to the rider rollers.

5 10. In an inking mechanism for a printing machine having a rotary ink cylinder, a shaft for the cylinder, means for rotatably driving the rotary ink cylinder, a rotary member rotatably driven by the rotary ink cylinder, means carried by the rotary member for operably engaging the rotary ink cylinder to impart reciprocatory movement thereto, axially stationary rotatable ink rollers operably engaging the ink cylinder and rotatable thereby, rider rollers operably engaging the axially stationary ink rollers and mounted for reciprocation relative to the ink rollers, a yoke rotatably supported on the shaft of the ink cylinder but secured against axial movement relative thereto, and means for rotatably securing the rider rollers to the opposed terminals of the yoke, the rider rollers being secured against axial movement relative to the yoke whereby reciprocatory movement of the ink cylinder imparts reciprocatory movement to the rider rollers.

15 20. 11. In an inking mechanism for a printing machine having a rotary ink cylinder, a shaft extending axially from the rotary ink cylinder, means for rotatably driving the rotary ink cylinder, a rotary member, a roller secured to the ink cylinder shaft and rotatable with the ink cylinder, annular ribs carried by the roller, and reversing helically disposed ribs carried by the rotary member and frictionally engaged by the annular ribs of the roller whereby rotation of the roller imparts rotary movement to the rotary member and the said helically disposed ribs of the rotary member impart reciprocatory movement to the ink cylinder.

25 30. 35. 12. In an inking mechanism for a printing machine having a rotary ink cylinder, a shaft extending axially from the rotary ink cylinder, means for rotatably driving the rotary ink cylinder, a rotary member, a roller secured to the ink cylinder shaft and rotatable with the ink cylinder, annular tapered ribs carried by the roller, and reversing helically disposed tapered ribs carried by the rotary member, the tapered portion of the said helically disposed ribs of the rotary member frictionally engaging the tapered portion of the annular ribs of the roller whereby rotation of the roller imparts rotary movement to the rotary member and the said helically disposed ribs of the rotary member impart reciprocatory movement to the ink cylinder.

40 45. 50. 55. 13. In an inking mechanism for a printing machine having a plurality of rotary ink cylinders, a shaft extending axially from each ink cylinder, means for rotatably driving the rotary ink cylinders, a roller secured to each ink cylinder shaft and rotatable with the cylinder, annular ribs extending radially from the peripheral portion of each roller, a cylindrical member surrounding the rollers and mounted for rotation, and reversing helically disposed ribs extending radially inwardly from the cylindrical member and operably engaging the annular ribs of the rollers whereby the rotation of the rollers imparts rotary movement to the cylindrical member and the said helically disposed ribs of the cylindrical member impart reciprocatory movement to the ink cylinders.

60 65. 70. 75. 14. In an inking mechanism for a printing machine having a plurality of rotary ink cylinders, a shaft extending axially from each ink cylinder, means for rotatably driving the rotary

ink cylinders, a roller secured to each ink cylinder shaft and rotatable with the cylinder, annular ribs extending radially from the peripheral portion of each roller, a cylindrical member surrounding the rollers, a rotatably supported hub portion for the cylindrical member to thereby rotatably support the cylindrical member, and reversing helically disposed ribs extending radially inwardly from the cylindrical member and operably engaging the annular ribs of the rollers whereby the rotation of the rollers imparts rotary movement to the cylindrical member and the said helically disposed ribs of the cylindrical member impart reciprocatory movement to the ink cylinders.

15. In an inking mechanism for a printing machine having a rotary ink cylinder, means for rotatably driving the rotary ink cylinder, a rotary member, a roller secured to and rotatable with the ink cylinder, annular ribs carried by the roller, reversing helically disposed ribs carried by the rotary member and operably engaging the ribs of the roller, a gear carried by the rotary member, gears driven from the cylinder and operably engaging the gear of the rotary member to impart rotation thereto by the rotary movement of the cylinder, the said helically dis-

posed ribs of the rotary member operably engaging the ribs of the roller to impart reciprocatory movement to the roller and cylinder when the rotary member is rotated by the rotation of the cylinder.

16. In an inking mechanism for a printing machine, a rotatable ink cylinder having a shaft, an annularly ribbed roller rotatable on the ink cylinder shaft but held against axial movement thereon, a rotatable ring having reversing internally disposed helical ribs arranged to engage the ribbed roller, and gearing to rotate the ring and thereby reciprocate the ink cylinder.

17. In an inking mechanism for a printing machine, a rotatable ink cylinder having a shaft, an annularly ribbed roller rotatable on the ink cylinder shaft but held against axial movement thereon, a rotatable ring having reversing internally disposed helical ribs arranged to engage the ribbed roller, means to rotate the ring and thereby reciprocate the ink cylinder, and means to change the speed of rotation of the ring and thereby change the speed of the reciprocation of the ink cylinder with respect to the speed of the machine.

WILLIAM F. HUCK.
